US0D1084522S

(12) **United States Design Patent** (10) **Patent No.:** **US D1,084,522 S**
(45) **Date of Patent:** **** Jul. 15, 2025**

(54) **POUCH**

(71) Applicant: **Henkel AG & Co., KGaA**, Duesseldorf (DE)

(72) Inventor: **Emil Tarnowsky**, Brampton (CA)

(73) Assignee: **Henkel AG & Co. KGaA**, Duesseldorf (DE)

(**) Term: **15 Years**

(21) Appl. No.: **29/869,943**

(22) Filed: **Jan. 12, 2023**

(51) LOC (15) Cl. **28-02**

(52) U.S. Cl.

USPC **D28/8.1**

(58) **Field of Classification Search**

(57) **CLAIM**

The ornamental design for a pouch as shown and described.

DESCRIPTION

FIG. 1 is a top, front isometric view of a first embodiment of a pouch showing the claimed design;
FIG. 2 is a bottom, rear isometric view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a top, front isometric view of a second embodiment of a pouch showing the claimed design;
FIG. 10 is a bottom, rear isometric view thereof;
FIG. 11 is a front elevation view thereof;
FIG. 12 is a rear elevation view thereof;
FIG. 13 is a left side elevation view thereof;
FIG. 14 is a right side elevation view thereof;
FIG. 15 is a top plan view thereof; and,
FIG. 16 is a bottom plan view thereof.

The broken lines in the figures show portions of the pouch that form no part of the claimed design.

1 Claim, 8 Drawing Sheets
